US0D1035446S

(12) **United States Design Patent** (10) **Patent No.:** **US D1,035,446 S**
(45) **Date of Patent:** **** Jul. 16, 2024**

(54) **CONTAINER WITH LID**

(71) Applicant: **Reynolds Presto Products Inc.**, Lake Forest, IL (US)

(72) Inventor: **Ari Syrquin**, Mexico City (MX)

(73) Assignee: **REYNOLDS PRESTO PRODUCTS INC.**, Lake Forest, IL (US)

(**) Term: **15 Years**

(21) Appl. No.: **29/868,073**

(22) Filed: **Nov. 18, 2022**

(51) LOC (14) Cl. **09-01**

(52) U.S. Cl.

USPC **D9/547; D7/629**

(58) **Field of Classification Search**

(57) **CLAIM**

The ornamental design for a container with lid, as shown and described.

DESCRIPTION

FIG. 1 is an isometric perspective view of a container with lid illustrating my new design;

FIG. 2 is a front elevation view thereof;

FIG. 3 is a rear elevation view thereof;

FIG. 4 is left side elevation view thereof;

FIG. 5 is right side elevation view thereof;

FIG. 6 is a top plan view thereof; and,

FIG. 7 is a bottom plan view thereof.

The dashed lines in the drawings depict portions of the container with lid that form no part of the claimed design. The dash-dot lines in the drawings depict boundaries of the claimed design that form no part thereof.

1 Claim, 7 Drawing Sheets
